FIG. 6

FIG. 7

FIG. 1 is a top plan view of a bottle or similar article embodying my new design;

FIG. 2 is a bottom plan view thereof;

FIG. 3 is a side elevational view thereof, the other side being substantially a mirror image of the side shown;

FIG. 4 is a rear elevational view thereof with the shovel portion of my design moved to the raised position;

FIG. 5 is a front elevational view of FIG. 4;

FIG. 6 is a rear elevational view of FIG. 3;

FIG. 7 is a side elevational view of FIG. 4, the other side being substantially a mirror image of the side shown;

FIG. 8 is a top plan view of a modified form of a bottle or similar article showing my design provided with a roller attachment, the curved surface of said roller attachment being substantially symmetrical; and

FIG. 9 is a side elevational view of the embodiment of my design shown in FIG. 8 with the roller portion moved to the raised position, the other side being substantially a mirror image of the side shown.

The essential features of my design reside in the portion illustrated in solid lines.

I claim:

The ornamental design for a bottle or similar article, as shown and described.
